UNITED STATES PATENT OFFICE.

CLARENCE SPENCER HART, OF NEW YORK, N. Y.

TOILET ARTICLE FOR HAIRDRESSING.

Application filed November 24, 1926. Serial No. 150,497.

This invention relates to a toilet article for hairdressing purposes.

One of the objects of the present invention is to provide such an article having in combination a brush and a comb associated with the back of said brush.

A further object of the invention is to associate the comb with the brush-back in such a manner that the comb is movable relatively to said brush-back into and out of an operative position.

A further object of the invention is to provide a toilet article for hairdressing purposes which comprises in combination a brush and a mirror affixed to the back of said brush.

Further objects of the invention will appear in the following description of the drawings and in the claims.

20 In the drawings:—

Fig. 1 is a perspective view of a toilet article according to this invention showing the comb in the operative position.

Fig. 2 is a rear elevation of the article 25 with the comb in the inoperative position and illustrating a mirror affixed to the brush-back.

Fig. 3 is a section on the line 3—3 of Fig. 2.

30 Fig. 4 is a section on the line 4—4 of Fig. 3.

Figs. 5 and 6 are two sectional views taken on the line 5—5 of Fig. 4, illustrating in the upper view the relative positions of 35 the parts when the comb is in the inoperative position and illustrating in the lower view the relative positions of the parts when the comb is in the operative position.

The toilet article illustrated in the drawings 40 consists of a hair brush comprising bristles *a* affixed by any conventional method to one face of a wooden brush-back *b* having, in the example illustrated, an integral handle *c*.

45 Within the thickness of this brush-back is cut or otherwise formed an elongated recess which is open on one longitudinal edge of the brush-back only. Extending from the bottom of this recess through the thickness of the brush-back to the opposite longitudinal edge of the same is a slot *d* which is smaller in both dimensions than the aforesaid recess.

50 Located within the said recess is a metal lining *e* which corresponds in all respects to the interior shape and dimensions of the re-

cess. The bottom *f* of this liner is cut away as at *g* to form an opening corresponding to the slot *d*.

Located within the lined interior of the 60 said recess is a U shaped metal frame *h* to the back of which is affixed a stem *i* which extends through the slot *d*, the outer end thereof being formed or otherwise provided with a knob *j*. The frame *h* is a sliding fit 65 within the lined recess and the longitudinal dimension of the same is such as will permit such frame to have a predetermined extent of sliding movement which is imparted to it by the operator through the medium 70 of the knob on the outer end of the stem *i*.

Cut in the opposite side walls of the frame *h* are pairs of inclined slots *k*, the extremities of which curl over as indicated in Fig. 4. Engaging in these pairs of slots are pins 75 *l* which are carried by and project from opposite sides of a comb *m* which is adapted so as to be a sliding fit laterally within the lined recess in the brush-back.

As a result of the above construction 80 movement downwards of the knob *j* and consequent like movement of the frame *h* causes the comb to move laterally inwards between the sides of the frame and into the interior of the recess. Movement of the knob and 85 frame causes the comb to be moved out of the recess to the operative position shown in Fig. 4.

In the example illustrated a bevelled or other mirror *n* is affixed within a recess on 90 the upper face of the brush-back as will be clearly seen upon reference to Figs. 2 and 3 of the drawings.

There is thus provided in one article the three components normally used in the 95 operation of dressing a person's hair.

What I claim is:—

1. A toilet article for hairdressing purposes comprising in combination a brush, an elongated recess within the thickness of the 100 back of said brush, a member located within said recess and adapted to be longitudinally movable therein, inclined slots in said member, a comb, pins projecting from said comb and engaging said inclined slots and 105 means for sliding said member longitudinally up and down within said recess so as to cause said comb to move laterally into and out of said recess.

2. A toilet article for hairdressing purposes comprising in combination a brush, 110 an elongated recess extending inwards from

- one edge of the brush-back, a slot extending from the bottom of said recess through the brush-back to the opposite edge of the same, a lining within said recess, a U shaped member located within said lined recess and adapted to be longitudinally movable therein in opposing inclined slots in the sides of said U shaped member, a comb, pins projecting from opposite sides of said comb and 10 slidably engaging said inclined slots and means for sliding said U shaped member longitudinally up and down within said recess so as to cause said comb to move laterally into and out of said recess comprising 15 a stem affixed to the inner longitudinal edge of said U shaped member and extending through the slot in the thickness of the brush-back to a position where the same may be grasped by the fingers.
- 20 3. A toilet article for hairdressing purposes comprising in combination a brush, an elongated recess extending inwards from one edge of the brush back a slot extending from

the bottom of said recess through the brush back to the opposite edge of the same, a 25 comb laterally slideable within said elongated recess, a pin longitudinally movable in said slot and means serving to interconnect said pin with said comb whereby movement of said pin causes said comb to move in or out 30 of its recess.

4. A toilet article for hairdressing purposes comprising in combination a brush, a mirror mounted upon the back of said brush, an elongated recess extending inwards from one edge of the brush back, a slot extending from the bottom of said recess through the brush back to the opposite edge of the same, a comb laterally slideable within said elongated recess a pin longitudinally movable in 35 said slot and means serving to interconnect said pin with said comb whereby movement of said pin causes said comb to move in or out of its recess.

In testimony whereof I affix my signature.
CLARENCE SPENCER HART.
